UNITED STATES PATENT OFFICE.

JOHN H. HUNT, OF DAYTON, OHIO, ASSIGNOR TO THE DAYTON ENGINEERING LABORATORIES COMPANY, A CORPORATION OF OHIO.

IGNITION CONTROLLER.

Application filed September 27, 1918. Serial No. 255,912.

To all whom it may concern:

Be it known that I, JOHN H. HUNT, a citizen of the United States of America, residing at Dayton, county of Montgomery, State of Ohio, have invented certain new and useful Improvements in Ignition Controllers, of which the following is a full, clear, and exact description.

This invention relates to devices for controlling the ignition systems of internal combustion engines, and has for one of its objects a provision of means for temporarily disabling the ignition apparatus so as to permit coasting of the engine while the vehicle propelled by the engine is moving.

More particularly, it is an object of the invention to provide controlling devices for ignition systems of internal-combustion engines used in airplanes, in such a manner that the aviator can with one hand direct the course of the airplane while in flight or in motion on the ground, and at the same time disable the ignition apparatus temporarily so that the engine may coast. As a means of carrying out this object the handle of control lever, sometimes known as the "joy stick," and used for moving the elevators and ailerons, is provided with a switch which is conveniently located thereon. This switch is adapted when manually operated, to disable temporarily the ignition apparatus. In this manner it is possible for the aviator, with one hand to move the control lever and at the same time operate the switch with the same hand.

Other and further objects of the present invention will be apparent from the following description, a preferred embodiment of the present invention is clearly shown.

In the drawings:—

Fig. 1 is a wiring diagram showing electrical connections included in the present invention.

Fig. 2 is an end view of the switch included in the present invention.

Fig. 3 is a section taken on the line 3—3 of Fig. 2 of the switch and shows also a fragmentary sectional view of the control lever in which the switch is located, and,

Fig. 4 is a section of a fragmentary side view of the fuselage of an airplane showing the relative location of the aviator's seat and the control lever provided with a switch for controlling the ignition.

Referring to the drawings, 20 refers to a

V-type engine, shown diagrammatically, and 21 and 22 are ignition timing devices which are mechanically connected to the engine by suitable gearing, not shown, and which provide for the intermittent making and breaking of the current used for ignition purposes. 23 and 24 are the primary windings of ignition coils, and 25 and 26 are the secondary windings of the ignition coils which cooperate with windings 23 and 24, respectively. The secondary windings 25 and 26 are connected in a suitable manner with the distributors 27 and 28 which are constructed and arranged to distribute the sparking impulses of the various spark plugs of the engine, which are not shown. Condensers 35 and 36 are connected in parallel with timers 21 and 22, respectively.

30 is a generator adapted to be driven by the engine by means of suitable mechanical connections, not shown, and 31 is a storage battery or other suitable source of current. 32 and 33 are switches by means of which the generator or the battery, or both, may be connected to the ignition coils for supplying current for ignition purposes.

The operation of this part of the device will be apparent from diagram shown in Fig. 1. The switches 32 and 33 being closed and circuit being completed through the timers 21 and 22, the coils 23 and 24 will be energized by the current passing therethrough. When ever the primary circuit is broken in the timers 21 and 22, sparking impulses will be induced in the secondary windings 25 and 26, and will be distributed by distributors 27 and 28 in order to supply the engine with ignition at the proper time.

Where the ignition described is used on an airplane the switches 32 and 33 are usually located on the instrument board or on some other relatively stationary part of the airplane. Therefore, if it should be necessary to permanently disable the ignition apparatus, as when the engine comes to rest on the ground, the aviator will reach forward from his seat and open the switches 32 and 33. But during flight it may be desirable to disable temporarily the ignition apparatus so that the engine will not fire and will coast. It is desirable to accomplish this result by some manually operated device which can be operated by the aviator by using the same hand which operates the

control lever for controlling the elevator and ailerons.

As a practical embodiment of such a device, the handle of the control lever 40, see Fig. 4, has been provided with a switch located in the upper end thereof, said switch being designated as a whole by numeral 41.

The control lever 40 which is generally tubular in form is recessed at the upper end 10 to provide a mounting for the switch 41. This recess extends as far as the ledge 42, see Fig. 3.

The switch 41 comprises a cup shaped member 43 having an external diameter 15 such as to permit the switch to fit snugly within the end of the handle of lever 40. The member 43 is provided with a flange 44 and is formed so as to provide a cover for the upper end of the lever 40, in order 20 to present a neat appearance. The screws 45 passing through the lever 40 secure the member 43 in position. Member 43 is provided with a recess 46 in which is positioned a spring 47. This spring 47 bears 25 at one end against 43, and at the outer end against the button 48 which is mounted upon a plunger 49. This plunger 49 projects into the cup shaped member 43 and carries on its inner end a movable contact 50.

Secured upon the inner end of the member 43 is base member 51 preferably made of insulating material. The base 51 carries posts 52, 53 and 54, made of conducting material. These posts are provided at one end 35 with nuts 55 by means of which wires 56, 57 and 58 are connected to the posts 52, 53 and 54 respectively.

The posts 52, 53 and 54 project into the cup shaped member 43, and the inner or 40 head ends thereof are so related as to be simultaneously engaged by the movable contact 50. The posts 52 and 53 are each provided with an insulating portion 59 upon which is mounted a resistance element 60. 45 This resistance element 60 is connected in series between the nut 55 and the inner or head end of each of the posts 52 and 53.

Referring to Fig. 1, it will be seen that the wires 56 and 57 connect the posts 52 and 50 53 respectively, with the primary ignition coils 23 and 24, respectively, at points between said coils and their respective ignition timers 21 and 22. The wire 58 makes a connection from the post 54 to ground, which is 55 usually the frame of the engine 20. Use is made of the tubular construction of the lever 40 as a casing for the wires 56, 57 and 58, which lead out from the lower end of the lever 40, see Fig. 4, and are connected in a 60 suitable manner at the locations described.

Assuming that the engine is self-operative and the switches 32 and 33 closed, and that it is desired to coast, while the hand of the operator is upon the control lever 40 65 controlling the flight of the airplane, the

aviator moves his finger to the button 48 and presses it inwardly. Then, when the timer contacts are opened, the primary circuit will not be broken since current from the generator 30 may find its way back through wires 56 and 57, resistances 60 and ground connection 58. By reason of the connection of resistance elements 60 in parallel with condensers 35 and 36, the usual action of the condensers is hindered to such an extent, 70 that when the timer contacts open, sparking impulses will be obtained which are insufficient for ignition purposes.

The resistances 60 also prevent undue discharge of the battery when the switch 41 is 80 operated.

When it is desired to again cause the engine to be self-operative, the button 48 is released and the ignition system will become operative to fire the engine in the 85 usual manner.

When the form of mechanism herein shown and described constitutes a preferred form of embodiment of the invention, it is 90 to be understood that other forms might be adopted, all coming within the scope of the claims which follow:

1. In an automotive vehicle having an internal-combustion engine, the combination of a member for controlling the direction of movement of the vehicle; a main ignition circuit for the engine, including a source of direct current, an ignition coil, a timer and circuit connections therebetween; switch mechanism for rendering said ignition circuit inoperative to provide ignition while the main circuit remains intact, said mechanism serving to limit the passage of current from said current source; and manually operable means for controlling the switch mechanism, said means being movable with the said member.

2. In an airplane having an internal-combustion engine and a member movable to control movements of the airplane, the combination of a main ignition circuit for the engine including a source of direct current, an ignition coil and a timer; an auxiliary circuit operating while the main circuit is intact, for rendering the ignition inoperative to fire the engine, and for limiting the passage of current from the current source; and a manually controllable switch in the auxiliary circuit, said switch being mounted on and movable with the said member.

3. In an airplane having an internal-combustion engine and a hollow joy stick, the combination of a main ignition circuit for the engine including a current source, an ignition coil, a timer and circuit connections therebetween; and an auxiliary circuit for rendering said main circuit inoperative to produce ignition, said circuit including a unitary switch mechanism mounted in the joy stick and provided with a resistance

element, terminals connected in a normally open shunt with the timer, and manually operable means for completing the shunt circuit through the terminals and resistance unit.

4. In a device of the kind described, the combination with an airplane steering control lever of hollow construction; of a switch comprising a cup shaped body portion adapted to fit into the upper end of the control lever and to form a closure for said end an end portion cooperating with the body portion; contact posts mounted on the end portion, one of the posts being provided with a ground connection, and other of the posts being provided with resistance ele-

ments mounted thereon; and a manually controlled movable contact member mounted on the cup shaped body portion and adapted to cooperate with the posts; an ignition system for the airplane engine; and conductors leading from the switch down through the tubular steering control lever and connected with the ignition system, whereby, when the manually controlled movable contact is operated the ignition system will be rendered inoperative.

In testimony whereof I affix my signature.
JOHN H. HUNT.
